SOLE SKIVING MACHINE

Kenneth W. Macdonald, Watertown, Mass., assignor to Compo Shoe Machinery Corporation, Boston, Mass., a corporation of Delaware

Application October 27, 1941, Serial No. 416,631

24 Claims. (Cl. 12—17)

This invention relates to skiving or splitting machines and more particularly to a skiving machine for reducing and shanking out shoe soles.

In the manufacture of shoes, it is usual practice to prepare outsoles for attachment to the lasted shoe bottoms by a series of operations such as skiving or fleshing to desired thickness, forepart reducing, and shanking out. These operations require the use of separate machines, and location of the shanking out, degree of bevel obtained, and general finish depend entirely upon the skill of the operators. To avoid some of these objections, shanking out machines have been devised but they do not complete the skiving operation, and require considerable attention and changing of dies and matrices.

A general object of this invention is to provide a skiving machine which is capable of skiving outsoles to desired thickness, reducing the foreparts and shanking out in a single operation.

More specifically, objects of the invention are to provide a sole skiving machine with suitable matrices for reducing the foreparts and shanking out outsoles that are readily adjustable to accommodate varying sizes and widths.

Another object of the invention is to provide a mechanism for adjusting and indexing the positions of the matrices that is simple and positive in operation and readily accessible.

A further object of the invention is to provide a skiving machine having an upper roll equipped with adjustable matrices and a cooperating pressure and feed roll which is deformable and which will adapt itself to press an outsole into the matrices regardless of their size or positions.

A still further object of the invention is to provide novel means for driving the deformable pressure and feed roll in timed relation with the upper or matrix roll and yet allow the timed relation to be varied upon completion of a skiving operation in order to present another portion of the deformable pressure roll in alignment with the matrices to prevent undue wear.

Other objects of the invention will in part be obvious and will in part appear hereinafter.

The invention accordingly comprises the features of construction, combination of elements, and arrangement of parts, which will be exemplified in the construction hereinafter set forth and the scope of the invention will be indicated in the claims.

For a fuller understanding of the nature and objects of the invention, reference should be had to the following detailed description taken in

connection with the accompanying drawings, in which:

Fig. 1 is a vertical sectional view of a sole skiving machine embodying preferred features of the present invention, taken substantially along line 1—1 of Fig. 2;

Fig. 2 is a fragmentary plan view of the machine, parts being broken away better to illustrate the construction;

Fig. 3 is a vertical sectional view taken substantially along line 3—3 of Fig. 1;

Fig. 4 is a sectional view taken substantially along line 4—4 of Fig. 3;

Fig. 5 is a fragmentary sectional view taken substantially along line 5—5 of Fig. 4;

Fig. 6 is a sectional view taken substantially along line 6—6 of Fig. 3 to show detail of the deformable pressure roll driving clutch;

Fig. 7 is a fragmentary vertical sectional view taken substantially along line 7—7 of Fig. 8;

Fig. 8 is a partial vertical sectional view similar to Fig. 3 but showing work being depressed into the matrices;

Fig. 9 is a developed plan view of the component parts of the matrix roll as projected from Fig. 7 looking in the direction of the arrows 9—9;

Fig. 10 is a sectional view taken along line 10—10 of Fig. 9;

Fig. 11 is a sectional view taken substantially along line 11—11 of Fig. 9; and

Fig. 12 is a plan view of an outsole as reduced and shanked out by the machine shown in Figs. 1 to 11, together with the skiving removed therefrom during the operation.

A preferred form of skiving machine to which this invention may be applied comprising, opposed rolls having sufficient circumferential length to feed the entire length of an outsole past the skiving knife and having suitable sole locating, clamping, and presenting means, is generally shown in Card Patent No. 2,088,051, and adapting the novel features hereinafter described to this machine allows it to be utilized to great advantage in preparing outsoles for attachment to lasted shoe bottoms in a uniform, rapid and economical manner.

The present invention relates to improvements in and to the matrix roll, matrices, and feed or pressure roll, and hence the following description will be confined mainly thereto.

Referring to the drawings, there is shown a machine substantially the same as described in the above-mentioned Card patent, and the machine may comprise base members 14 at opposite sides of which are secured upright standards 15

and 16 joined at their upper ends by a tie bar 17.

A skiving knife 18 is adjustably secured to the table portion of the base 14 with its knife edge located near the center of the matrix roll 19 and the feed and pressure roll 20.

The matrix roll 19 is supported by a shaft 21 journalled in bearings 22 and 23 which are vertically adjustable in the standards 15 and 16. Integral and adjustable with the bearing 23 is a gear housing 24 to which is secured a stud 25 having a gear 26 freely rotatable thereon, and meshing therewith is a gear 27 of equal diameter which is secured to the shaft 21.

A shaft 28 is provided for supporting and driving the lower or feed and pressure roll 20. This shaft is journalled in bearings 29 and 30 which are slidable in the standards and are biased toward the upper roll by the heavy springs 31, suitable stops to prevent the lower roll from contacting the knife or the upper roll being provided.

One end of the shaft 28 is connected to the gear 26 and the other end to a suitable single revolution clutch (not shown) by means of couplings of the Oldham type, thus allowing the clutch to rotate the shaft 28, the gears 26 and 27, and the matrix roll shaft 21, even if the lower shaft 28 is not in axial alinement with the clutch or with gear 26.

The diameters of the rolls 19 and 20 are equal, and the diameters of the gears 26 and 27 are equal, and as means hereinafter described are provided for securing the rolls to the shafts, it is readily understood that one revolution of the feed roll shaft 28 will drive both the feed roll and matrix roll one revolution in timed relation and in opposite directions so as to feed outsoles presented to the rolls by devices described in the aforementioned Card patent past the skiving knife.

In order to skive outsoles of varying sizes and widths, adjustable matrix segments for operating upon the shank portion of the outsoles are provided, one pair 35 for opposite sides of the left outsole, and one pair 36 for opposite sides of a right outsole, the forepart portions of the outsoles being treated by separate matrices 37 and 38 cut directly into a portion of the roll, as best shown in Fig. 9 which is a developed plan view of the complete matrix roll and its component parts.

Referring more particularly to Figs. 7 to 11, which show a preferred form of matrix roll construction, keyed to the shaft 21 are hubs 40 and 41 to which two half rolls or segments 42 and 43 are secured by screws 44.

The segment 42 has matrices in the form of depressions 37 and 38 cut therein and which conform somewhat to the forepart portions of outsoles. It has been found that a composite shape can be determined from several distinct outsole patterns and, if the matrix is left large enough to give a minimum reduced edge around the forepart of the smallest size sole which may be in the order of size 4B, the largest soles will not have too wide a skived margin.

The segment 43 which carries the adjustable matrices has a diameter substantially corresponding to the diameter of the forepart segment 42 as measured at the bottom of the forepart matrix cavity, so that an outsole can be depressed into the matrices to an even depth both at the shank and forepart portions. The adjustable shank portion matrices 35 and 36 are in the form of cylindrical segments contoured and

bevelled to suit a complete run of outsoles, and each has a projecting key 47 on the underside thereof and may be integral with the matrix segments. The roll segment 43 which carries the matrix segments is provided with a series of spaced grooves 48 in which the keys of the matrix segments are adapted to slide. Slots 45 are cut entirely through the roll segment 43, and the screws 46 which are counterbored into the matrix segments pass through the slots and are screw-threaded into a form of adjusting segment 50, the screws being provided with appropriate shoulders which abut the adjusting segment 50 and also have sufficient body length to prevent clamping of the matrix and roll segments to the adjusting segment 50.

The internal and external diameters of the adjusting segment 50 are proportioned to allow it to be snugly confined between the internal diameter of the roll segments and the shaft 21, and rotation of the adjusting segment upon the shaft 21 will also cause rotation of the matrix segments 35 and 36 with respect to the roll segments.

In order to allow the leading edge of the shank matrices to overlap and be adjustable with respect to the forepart matrices, the keys 47 terminate somewhat behind the leading edge as best shown at 51, Fig. 11.

Provision of the adjustment between the shank and forepart matrices allows the start of the shanking-out operation to be varied so as properly to locate same at the ball line of the outsole, and one form of a simple but effective mechanism for rapidly making and indexing the adjustment is shown in Figs. 3, 4, 5, 7, and 8. The shaft 21 is provided with a bore 55 in which is arranged to slide a rod 56 having gear teeth 57 cut in the protruding end to form a rack.

Turned integral with shaft 21 is a collar 58 having a bore 59 therein to receive a pinion 60. The opposite sides of the bore 59 are counterbored to form flat faces 61, and the pinion 60 is confined between these faces by a head 62 formed integral with the pinion and a washer 63 secured to the opposite end of the pinion by a screw 64.

To keep the pinion teeth in alinement with the rack 57, a keyway 65 is cut in the center of the rod 56 and a form of screw key 66 is threaded into the collar 58 and has a dog point 67 engaging the keyway. At the end of the rod 56 opposite the adjusting pinion, a hole is bored at right angles in the center of the rod and a cam pin 68 is securely pressed therein. The cam pin 68 passes through a straight slot 69 in the wall of the shaft 21, the head of the cam pin engaging in a helical slot 70 cut in the adjusting segment 50.

Holes 71 in the head of the pinion gear 60 are provided for insertion of a form of wrench to turn the pinion, and rotation of the pinion 60 causes the rod 56 to slide in the bore of the shaft 21, and the cam pin 68 being in the helical slot 70 imparts a rotary motion to the adjusting segment 50 and the shank matrices 35 and 36.

To provide visual indication of the position of the shank matrices, the head of pinion gear 60 is indexed according to sole sizes as shown in Fig. 3.

In order to avoid accidental displacement of the shank matrix segments by vibration, etc., a detent 75 is secured to a leaf spring 76 held to the shaft collar 58 by a screw, and the spring biases the detent 75 into firm engagement with the teeth of the pinion 60, thus making it nec-

essary to use considerable force to effect rotation of the pinion or movement of the rod 56.

As the size and/or shape of the complete matrices alter according to the adjustment made to process any particular sizes of outsoles, it is not very practical to make a solid matrix or deformable member on the lower roll to press the outsole into the matrices; therefore a deformable feed and pressure roll 20 has been provided which automatically forms itself to the shape of the matrices. This deformable feed and pressure roll comprises an inner cylindrical roll 80 having molded thereon or otherwise secured thereto an outer cylinder of rubber-like compound 20 having a hardness within the limits of 70 to 80 "A" scale as measured by a Shore durometer. The inner roll 80 is provided with bearing bushings 81 and the complete roll is freely rotatable on the shaft 28, but is limited from endwise movement by being confined between the hubs 82 and 83.

If the roll is left free on shaft 28, no feeding effort would be imparted to an outsole presented for passage through the rolls, and if the roll 20 is fixedly secured to the shaft 28, the same portion of the rubber would always be presented to the matrices on the upper roll as both rolls are driven in timed relation and the constant distortion of the rubber in the same place would result in rapid deterioration.

To avoid these objections, an effective clutch arrangement is provided which allows both rolls to be driven in timed relation and yet which allows the timed relation of the rolls to be varied after each revolution so as always to present a different portion of the rubber roll to be deformed into the matrices at the next operation.

One form of suitable clutch arrangement is shown in Figs. 3 and 6 and comprises an inner clutch member 85 which is keyed to the shaft 28, an outer clutch member 86 turned integral with the inner roll cylinder 80, and a series of rollers 87 wedged between the inner and outer clutch members as the shaft 28 is rotated in the direction to feed a sole between the feed and matrix rolls.

This arrangement allows the complete feed roll to be freely rotatable on the shaft 28 in the direction of the feed, and as long as the shaft 28 is turning to feed a sole, the roll 20 and the roll 19 are driven in timed relation, but upon sudden stoppage of the rolls by the single revolution drive clutch (not shown) the bottom roll continues to turn as it overrides the clutch due to inertia, finally stopping by friction, and thus the timed relation of the rolls is altered and a different portion of the rubber roll 20 will cooperate with the matrices when the next outsoles are presented to the machine.

In operating the machine, the handle 34 is moved to open the sole presenting means and a pair of outsoles B are placed grain side up on the table 32, Fig. 2, and the toe gages 33 are adjusted according to the size of the soles to locate their foreparts properly with respect to the fixed matrices 37 and 38 which control the forepart reducing operation.

Upon release of the handle 34, the sole is aligned and then gripped by the presenting means, all as described in the Card patent. The pinion gear 60 is then indexed to the correct sole size which rotates the shank matrices 35 and 36 upon the roll 19 and locates the shank matrices with respect to the forepart matrices to ensure a correct start for the shanking out.

The single revolution drive clutch is then allowed to become operative so as to rotate the matrix, feed, and sole presenting rolls, and as the soles are fed between the matrix and feed rolls, they are distorted and are depressed into the matrices by the deformable feed roll 20 and are skived by the knife 18.

An outsole 99 as processed by the above described operation is shown in Fig. 12 together with the skiving 91 removed therefrom. It should be understood that the degree of bevel obtained at the forepart and/or shank portions can be varied simply by interchanging the matrices, which are readily removable from the machine.

Ordinarily outsoles are graded for thickness prior to the forepart reducing and shanking out operations, but unless they are skived considerable variation is present. The above described machine, in addition to the forepart reducing and shanking out operations, skives the sole to an even thickness, as once the upper or matrix roll is spaced from the knife to process soles of a given thickness, any excess stock will be removed as part of the skiving 91.

It will be seen that there has been provided a skiving machine that is well suited to perform in a single operation the complete reducing and skiving required to prepare an outsole for attachment to a shoe bottom.

Since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention, which, as a matter of language, might be said to fall therebetween.

Having described my invention, what I claim as new and desire to secure by Letters Patent, is:

1. In a sole skiving machine the combination comprising, a skiving knife, a matrix roll having fixed matrix depressions in the periphery thereof and adjustable matrices thereon; a co-operating feed and pressure roll, and means for rotating both of said rolls to feed an outsole past said skiving knife.

2. In a sole skiving machine the combination comprising, a skiving knife, a matrix roll having fixed matrices below its periphery and adjustable matrix segments above its periphery, a deformable feed and pressure roll, means for adjusting said matrix segments with respect to said matrix roll, and means for rotating both of said rolls.

3. In a sole skiving machine the combination comprising, a skiving knife, a matrix roll comprising two segments, fixed and adjustable matrices secured to said matrix roll, a deformable feed and pressure roll, means for adjusting said adjustable matrices with respect to the fixed matrices, and means for rotating both of said rolls.

4. In a sole skiving machine the combination comprising, a skiving knife, a matrix roll, matrices for treating the forepart portions of outsoles depressed in said matrix roll, matrices for treating the shank portions of outsoles adjustably secured to said matrix roll, a cooperat-

ing feed and pressure roll, and means for rotating both of said rolls.

5. In a sole skiving machine the combination comprising, a skiving knife, a matrix roll, matrix depressions formed in the periphery of said matrix roll for treating the forepart portion of soles, matrices adjustably mounted on said matrix roll for treating the shank portions of soles, means for adjusting said shank treating matrices toward and away from said forepart treating matrix depressions, and a feed and pressure roll cooperating with said matrix roll to feed soles past said skiving knife.

6. In a sole skiving machine having a skiving knife and opposed rolls for feeding a sole past the skiving knife, the combination comprising, a matrix roll, a matrix depression in said roll for treating the forepart portion of an outsole, an elevated matrix on said roll for treating the shank portion of an outsole, and means for varying the position of one of said matrices with respect to the other of said matrices.

7. In a sole skiving machine having a skiving knife and opposed rolls for feeding an outsole past the skiving knife, the combination comprising, a matrix roll, a matrix depression in fixed relation on said roll for treating one end of an outsole, a matrix for treating the other end of an outsole adjustably mounted on said roll and arranged to overlap said first mentioned matrix.

8. In a sole skiving machine having a skiving knife and opposed rolls for feeding a sole past the knife, the combination comprising, a matrix roll, a matrix depression on said roll for treating one end of an outsole, an elevated matrix on said roll for treating the other end of said outsole, and means for varying the relative position of said matrices with respect to each other.

9. In a sole skiving machine having a skiving knife and opposed rolls for feeding an outsole past the knife; the combination comprising, a matrix roll, a pair of matrices on said roll for treating opposite ends of an outsole, and means for varying the position of one of said matrices with respect to the other, and means to rotate said matrix roll and matrices as a unit.

10. In a sole skiving machine having a skiving knife and opposed rolls for feeding a sole past the knife, the combination comprising, a matrix roll, a matrix depression on said roll for treating the forepart portion of a sole, a matrix for treating the shank portion of said sole rotatably mounted on said roll, and means rotatable with said roll for rotating said shank treating matrix with respect to the roll and matrix depression.

11. In a sole skiving machine having a skiving knife and opposed rolls for feeding a sole past the knife, the combination comprising, a matrix roll, a matrix depression formed in said roll for treating the forepart portion of a sole, and a pair of matrix segments for treating the opposite sides of the shank portion of said sole rotatable on said roll towards and away from said forepart treating matrix.

12. In a sole skiving machine the combination comprising, a skiving knife, a rotatable matrix roll having a matrix depression in its periphery for treating the forepart portion of an outsole and an elevated matrix for treating the shank portion of said outsole, one of said matrices being arranged to overlap and be adjustable toward and away from the other, a feed and pressure roll rotatable in timed relation with said matrix roll, means for positioning a sole to properly locate its forepart with respect to its matrix, means

for positioning said matrices with respect to each other to properly locate the shank matrix with respect to said positioned sole, means for presenting said positioned sole to the matrix and feed rolls, and means for rotating both of said rolls to deform said outsole to the shape of the matrices and to feed it past the skiving knife.

13. In a sole skiving machine the combination comprising, a skiving knife, a matrix roll having a matrix depression below its periphery and a matrix elevated above its periphery for operating upon the forepart and shank portions of an outsole, a feed and pressure roll, means for positioning and presenting a sole to said rolls in relation to the position of said matrix depressions, means for adjusting the elevated matrix in relation to the positioned sole, and means for rotating both of said rolls to feed the sole past said knife.

14. In a sole skiving machine the combination comprising, a skiving knife, a matrix roll and a cooperating feed and pressure roll, means for rotating both of said rolls one complete revolution in timed relation, and means for varying the timed relation of said rolls after each has made approximately one complete revolution.

15. In a sole skiving machine the combination comprising, a skiving knife, a matrix roll and cooperating deformable feed and pressure roll, means for rotating both of said rolls one complete revolution in timed relation, and means for varying the timed relation of said rolls after each has made approximately one complete revolution.

16. In a sole skiving machine having a skiving knife, a matrix roll and a pressure roll each having a large enough circumference to feed a sole past the skiving knife in one revolution, the combination comprising, matrix segments rotatable on the matrix roll, means for rotating said segments, means for locking said segments in the desired position, and means on the pressure roll for forcing a sole into the matrices regardless of their position on said matrix roll.

17. In a sole skiving machine, the combination comprising, a skiving knife, a rotatable shaft having a matrix roll secured thereto, a rotatable shaft having a pressure roll rotatably mounted thereon, a one-way clutch connecting said pressure roll to its shaft, and means for rotating said shafts and rolls to feed a sole past said skiving knife.

18. In a sole skiving machine, the combination comprising, a skiving knife, a pair of rotatable shafts, a matrix roll secured to one of said shafts, a deformable pressure and feed roll freely rotatable in one direction on the other shaft, and means for rotating both of said shafts and rolls.

19. In a sole skiving machine, the combination comprising, a skiving knife, a matrix roll, a deformable pressure and feed roll, driving means for rotating both of said rolls, means for disconnecting said driving means after said rolls have made one complete revolution in timed relation, and means whereby said deformable pressure and feed roll can continue to rotate after said driving means is disconnected and the matrix roll has stopped rotating.

20. In a sole skiving machine, the combination comprising, a skiving knife, a matrix roll, a deformable pressure and feed roll, driving means for rotating said rolls in timed relation to feed a sole past said skiving knife, means for disconnecting said driving means after each roll has made one revolution and means for automatically varying the timed relation of said rolls upon completion of the sole skiving operation.

21. In a sole skiving machine the combination comprising, a skiving knife, a pair of rotatable shafts, a matrix roll secured to one shaft of said pair, a deformable feed and pressure roll freely rotatable on the other shaft in the direction of the feed, and means for rotating said shafts and said rolls one complete revolution in timed relation.

22. In a sole skiving machine the combination comprising, a rotatable shaft having a matrix roll secured thereto, matrices rotatably mounted on said matrix roll, a member having a cam slot secured to said matrices, a rod slidable in a bore in said shaft, and means on said rod engaging said cam slot whereby reciprocation of said rod will cause rotation of said matrices upon said matrix roll.

23. In a sole skiving machine the combination comprising, a skiving knife, a pair of rotatable shafts, a matrix roll secured to one of said shafts, a feed and pressure roll mounted on the other

5 of said shafts, matrices secured to and rotatable on said matrix roll, a rod slidable in a bore provided in said shaft having the matrix roll secured thereto, connections between said rod and said matrices for rotating said matrices, and means for rotating both of said shafts.

24. In a sole skiving machine the combination comprising, a skiving knife, a rotatable matrix roll, a matrix depression in the periphery of said 10 matrix roll for treating the forepart portion of an outsole, a matrix adjustable on said matrix roll for treating the shank portion of said outsole, a rotatable feed and pressure roll cooperating with said matrix roll to depress said outsole into said matrices, means for positioning said outsole with respect to said forepart treating matrix, means for positioning said adjustable matrix with respect to said sole positioning means, and means 15 for rotating both of said rolls to feed said outsole past said skiving knife.

KENNETH W. MACDONALD.
